UNITED STATES PATENT OFFICE.

ROBERT L. DOWNTON, OF ST. LOUIS, MISSOURI, ASSIGNOR OF ONE-HALF
TO JAMES W. S. DOWNTON, OF SAME PLACE.

DUST-COLLECTOR.

SPECIFICATION forming part of Letters Patent No. 409,025, dated August 13, 1889.

Application filed January 2, 1889. Serial No. 295,116. (No model.)

To all whom it may concern:

Be it known that I, ROBERT L. DOWNTON, of the city of St. Louis, in the State of Missouri, have invented a certain new and useful Improvement in Dust-Collectors, of which the following is a full, clear, and exact description, reference being had to the accompanying drawings, forming part of this specification, and in which—

10 Figure I is a vertical section through my improved dust-collector. Fig. II is an enlarged detail view illustrating the manner of adjusting the brushes. Fig. III is an enlarged section taken on line III III, Fig. I. Fig. IV is a similar view taken on line IV IV, Fig. I. Fig. V is an enlarged detail sectional view of the connection between the dead-air chamber and delivery-flue and adjacent parts. Fig. VI is a transverse section taken on line VI 15 VI, Fig. I. Fig. VII is a detail side elevation of the lower end of the machine.

20 My invention relates to a device intended more particularly for use in connection with flour and other mills for arresting and collecting their dust; and my invention consists in features of novelty hereinafter fully described, and pointed out in the claims.

25 I find that a large amount of fine dust that escapes the first settling action adheres to the wall of the vent-flue, and though a portion of this fine dust and flour is saved by the action of the incased brush or scraper shown in my application filed May 17, 1888, Serial No. 274,137, still there is considerable of it that 30 flows out with the current of air and is wasted. My object, therefore, is to provide means for saving this material.

35 Referring to the drawings, 1 represents an outer casing, the upper part $1\frac{1}{2}$ of which is 40 preferably of the same size from top to bottom and the lower part of which is preferably tapering or smaller at its lower end than at its upper end. The part $1\frac{1}{2}$ of this casing is provided with a tangential opening 2, through 45 which the dust-laden air enters.

50 3 represents an inner casing, the upper part 4 of which is preferably of the same size from end to end, and the lower part of which is tapering or smaller at its lower end than at its upper end, and this lower part has perfora-

tions 30, as shown in the drawings. This inner cylinder is smaller than the outer cylinder, forming an intervening chamber 5. The inner casing 34, I term a "vent-flue." Inside of the wall or part 4 of the vent-flue is a 55 screen or sieve 6, which, being smaller than the part 4 of the flue, forms a dead-air chamber 7.

8 represents a central shaft having bearing on a cross-piece 9 at its upper end and a 60 cross-piece 10 at its lower end. On the upper portion of this shaft are arms 11, to the outer ends of which are secured brushes or wipers 12. Each brush is inclosed by a housing or casing 13, as shown in Fig. III. The brushes 65 bear or rub against the inner surface of the screen 6 as the shaft 8 revolves. The brushes may be adjusted to bring the desired pressure against the screen at all times by means of set-screws 14, working in the backs of the 70 housings or casings 13 and jamming against dovetailed blocks 15, that carry the brushes and that slide in the horizontal ends 16 of the housing. Upon the shaft 8 are arms 17, which 75 extend into the dead-air chamber 7, and on their ends are scrapers 18.

19 represents a tube or delivery-flue connecting with the dead-air chamber at 20.

21 represents vertical rods or arms located in the dead-air chamber and secured to and 80 carried by the arms 17 or scrapers 18.

100 represents a trough forming the bottom of the dead-air chamber, upon the inner edge of which the arms 17 bear. To form a joint here that will exclude the air, I place a circular shield or ring 101 on the arms 17, that extends above the bottom of the screen 6 and beneath the top inner edge of the trough, thus forming a lap-joint.

At the lower end of the machine a cone or 90 cylinder 22 is located, and which is held concentrically within the cylinder by means of brackets or fastenings 23, by which it is secured to the cylinder. On the lower end of the shaft 8 may be secured a delivery-screw 95 or conveyer 24, and beneath this are arranged one or more pairs of valves 25. I have shown two pairs. Each pair is pivoted at 26 to the lower end of the casing, and each valve is provided with a counter-weight 27, which hold 100

the valves closed, as shown in Fig. I. As the flour and dust collect in the upper pair of valves, it finally (owing to its weight) opens the valves and flows through to the next pair. 5 Before the lower pair opens the first pair has closed, thus insuring against the slightest influx of air.

The operation of my improved machine is as follows: The dust and air enter the chamber 5 through the opening 2, and the air escapes through the vent-flue 3 4, passing through the perforations 30. The flour or dust that is contained in the air as it escapes through the vent-flue settles on the inner surface of the screen 6 for the following reason: 15 The discharge-air in the vent-flue does not fill the whole area, but escapes in a ring about three inches thick on the outside edge of the air-flue, and the air rotates in a spiral whirl, 20 ascending up with a centrifugal action, so that the dust that gets into this vent-flue is thrown to the outside edge of this ring of air, and of course is impinged on the surface of the wire sieve, and is forced through to the inside of 25 the space between the imperforate and perforate wall of the vent-flue, where the air speed is reduced so that it is easier for the flour and dust to fall down into the trough than it is for it to escape at the top of the vent-flue. 30 The revolving brushes or wipers force it through the meshes of the screen into the dead-air chamber 7, where, there being no current of air, it settles, and is deposited by the scraper 8 into the flue 19, which delivers it to 35 the center of the machine, from whence it falls into the valves 25.

By incasing the brushes the immediate surface being rubbed by them is protected from the action of the escaping air, and the flour or dust is prevented from being carried out by the air-current and is forced by the brushes into the dead-air chamber. By the use of the cone or cylinder 22 a slower flow of air around the outer cylinder is produced, so that the flour and dust will settle more readily than when the outer surface is exposed to the full velocity of the air-current. The brushes 12 are rotary—that is, they are mounted on central pins or journals 50, in which they turn 45 as the shaft revolves—and by making the brushes so as to turn on their supports, as well as to revolve as a whole with the shaft, they are less liable to become clogged by the flour and better serve the purpose of forcing 50 the flour through the mesh of the screen.

It is possible that in some instances the brushes might be dispensed with and the air-current relied upon to force the flour or dust through the screen into the dead-air chamber; and, believing that I am the first to construct a machine having a dead-air chamber in connection with a centrifugal dust-collector, I do not wish to be confined to the use of 55 brushes in combination with the chamber.

65 I claim as my invention—

1. In a centrifugal dust-collector, in combination with an outer casing having a tan-

gential inlet, a screen and wall forming a dead-air chamber, against which the flour or dust is deposited under the action created by 70 the inlet being tangential, substantially as set forth.

2. In a centrifugal dust-collector, in combination with an outer casing having a tangential inlet, a screen and wall forming a 75 dead-air chamber, against which the flour or dust is deposited under the action created by the inlet being tangential, and brushes for forcing the flour or dust into the dead-air chamber, substantially as set forth. 80

3. In a dust-collector, in combination with an outer casing having a tangential inlet, a screen and wall forming a dead-air chamber against which the flour or dust is deposited under the action created by the inlet being 85 tangential, and brushes rotating on their axes bearing against the inner face of the dead-air chamber and forcing the material through the meshes, substantially as set forth.

4. In a dust-collector, the combination of 90 an outer casing having a tangential inlet, a wall and screen forming a dead-air chamber, a central shaft, and incased brushes on the shaft bearing against the screen and forcing the material through the meshes, substantially 95 as set forth.

5. In a centrifugal dust-collector, the combination, with the concentric outer casing, a wall and a screen forming a dead-air chamber in the outer part of the machine, of a 100 central shaft and adjustable brushes carried by the shaft and moving over said perforated wall, said outer casing having a tangential inlet, substantially as set forth.

6. In a centrifugal dust-collector, the combination of an outer casing provided with an inlet and with an outlet for purified air, a wall and screen forming an annular dead-air chamber located in the upper part of said casing and surrounding said air-outlet, a trough 110 forming the bottom of the dead-air chamber, a delivery-spout and scrapers, said casing having a tangential inlet, whereby the dust is separated from the air and passes through said screen, substantially as set forth. 115

7. In a dust-collector, the combination of an outer casing having a tangential inlet and an outlet, an inner casing forming a vent-flue, and brushes, the lower end of said vent-flue being perforated and the upper end having a 120 wall and screen forming a dead-air chamber, substantially as set forth.

8. In a dust-collector, the combination of an outer casing having a tangential inlet and an outlet, an inner casing forming a vent-flue, 125 and incased brushes, the lower end of said flue being perforated and the upper end having a wall and screen forming a dead-air chamber, substantially as set forth.

9. In a centrifugal dust-collector, the combination, with an outer casing having a tangential inlet, an inner casing forming a vent-flue, and a screen forming an annular dead-air chamber surrounding said flue, a trough 130

forming the bottom of the dead-air chamber, a delivery-spout, and scrapers, substantially as set forth.

10. In a centrifugal dust-collector, the combination of an outer casing having a tangential inlet, an inner casing forming a vent-flue, a screen forming, in connection with said inner casing, an annular dead-air chamber, a trough forming the bottom of the dead-air chamber, a delivery-spout, a shaft, arms on the shaft, and scrapers on the arms, substantially as set forth.

11. In a centrifugal dust-collector, the combination of an outer cylinder having a tangential inlet, an inner casing forming a vent-flue, a screen forming in connection therewith a dead-air chamber, a trough forming the bottom of the dead-air chamber, a delivery-spout, scrapers, and arms 21, for the purpose specified, substantially as set forth.

12. In a centrifugal dust-collector, the combination of an outer casing having a tangential inlet, an inner casing forming a vent-flue, a wall and screen forming a dead-air cham-

ber, a trough forming the bottom of the dead-air chamber, a central shaft, arms on the shaft, scrapers on the arms, and a shield 101, substantially as set forth.

13. In a dust-collector, the combination of an outer casing having a tangential inlet, an inner casing forming a vent-flue, a screen forming, in connection with said inner casing, a dead-air chamber, incased cleaning-brushes, and means for adjusting the brushes, consisting of dovetailed blocks and set-screws, substantially as set forth.

14. In a dust-collector, the combination of the outer casing having a tangential inlet, an inner casing forming a vent-flue, a screen forming, in connection with said inner casing, a dead-air chamber for catching the dust, and rotary brushes 12, having suitable journals and arranged within the vent-flue, substantially as set forth.

ROBERT L. DOWNTON.
